UNITED STATES PATENT OFFICE.

JOHN B. GAJ, OF DETROIT, MICHIGAN.

STOVE ATTACHMENT.

Application filed September 21, 1922. Serial No. 589,592.

To all whom it may concern:

Be it known that JOHN B. GAJ, a citizen of Poland, residing at Detroit, in the county of Wayne and State of Michigan, has invented certain new and useful Improvements in Stove Attachments, of which the following is a specification.

This invention relates to a pump attachment for a stove or range having a cooking top and an exhaust, the attachment being mounted on the end of the stove so that air in or about the attachment may be heated by the stove.

My invention aims to provide a pump attachment including a multi-cylinder pump which may be operated for numerous purposes.

First, certain cylinders of the pump may be used to supply air to the exhaust flue of the stove to produce a draft therein and thus increase the efficiency of the stove, as a fuel burner, should there be a defective chimney.

Second, the same pump cylinder may be used for supplying warm air to the rooms of a house, especially when such cylinders are shut off from the exhaust flue of the stove.

Third, the pump includes a cylinder communicating with the cooking top and flue of the stove, so that cooking fumes, odors or burned gases may be withdrawn from the cooking top and discharged to the atmosphere by virtue of the exhaust flue of the stove.

Fourth, instead of using the air under pressure for either heating or force draft purposes, the air may be directed against a fan to cause better ventilation or circulation of air in a room, the fan being substituted for an ordinary gas burner.

The attachment will be hereinafter described by aid of the drawings, wherein—

Figure 1 is a perspective view of a stove or range, provided with the attachment, and showing pipes that may lead to compartments or rooms, especially one having a gas burner, which may be equipped with a fan;

Fig. 2 is a detail view of a gas burner provided with a fan adapted to be driven by air from the pump of the attachment;

Fig. 3 is a plan of the same;

Fig. 4 is a longitudinal section of the attachment;

Fig. 5 is a cross sectional view taken on the line V—V of Fig. 4;

Fig. 6 is a horizontal sectional view taken on the line VI—VI of Fig. 4;

Fig. 7 is a vertical section on line VII—VII of Fig. 4;

Fig. 8 is detail view of a suction head, and

Fig. 9 is a plan of a "star" burner such as is replaced by a fan.

In the drawings, the reference numeral 75 denotes a conventional form of stove or range having a cooking top 16 and an exhaust flue 24 communicating with a stack or chimney, and my attachment is mounted at one end of the stove against a wall of the flue 24 or a similar stove flue.

The attachment includes a casing having side walls 1 and 2, a bottom wall 4, a top wall 3, and end walls 5 and 6, said walls being made of sheet metal finished to harmonize with the finish of the stove. The 75 casing may fit under a shelf 70 or an extension of the cooking top 16 of the stove.

In the casing, parallel to the end walls 5 and 6, are partitions 7 and 8 providing end compartments 78, and connecting the partitions 7 and 8 are horizontal partitions 76 and 77.

On the partition 77 are a plurality of pump cylinders 9, 10, 11 and 12, constituting a multi-cylinder pump, the cylinders 9, 85 10 and 11 having upper open ends and the cylinder 12 having a head 13. Connected to the head 13 is a pipe 14 extending out of the end wall 6 of the casing and along the front wall of the stove to a point where it enters the cooking top 16 and is provided with a suction head 17. On the pipe 14 is a check valve 15 and this valve, as well as others to be hereinafter referred to, is of a conventional form opening in the direction 95 of the flow of air.

In the cylinders 9, 10, 11 and 12 are pistons 18 provided with check valves 19 which admit air on the upstrokes of the pistons so that on the down strokes of said pistons the air can be forced out of the lower ends of the cylinders. The lower ends of the cylinders 9, 10 and 11 are connected by pipes 27 and check valves 28 to a header 29 below the partition 77 and said header is connected by a pipe 79 to a reservoir or tank 30 on the bottom wall 4 of the casing. This reservoir is adapted to receive air from the pump and

connected to the reservoir is an outlet pipe 35 provided with dampers 36 and branch pipes or flues that may extend to rooms of a house.

5 The side wall 2 of the casing has air inlet openings 80 and air admitted thereby will be more or less heated by the end of the stove 75, so that when pumped through the pipe 35 the air may heat rooms or cause a 10 circulation of air for better ventilating purposes.

In the case of the cylinder 12, the bottom thereof has an outlet pipe 23, provided with a check valve 26, extending through the wall 1 and into the flue 24 of the stove, so that 15 fumes, cooking odors or burned gas may be exhausted to the atmosphere.

Connected to the sides of the cylinders 9, 10 and 11, contiguous to the lower ends 20 thereof, are pipes 32 and 33, the latter extending through the wall 1 into the stove flue 24 where said pipes have ends curved towards the outlet of said flue. These same pipes have articulated slide dampers or 25 valves 34 operable by a rod 81 extending through the end wall 6 of the casing, and manual actuation of the rod 81 may open or close the dampers.

On the pipe 79 is a valve 31 operated by a 30 rod 82 extending through the casing end wall 6 and with this valve closed and the dampers 34 open, air may be pumped into the flue 24 to increase the draft therein and cause better burning of fuel in the stove 35 and a better circulation of heated air about 40 the oven of the stove. With the dampers 34 closed and the valve 31 open, air may be pumped to the rooms of a house.

Further use of the air pumped into the 45 pipe 35 may be had by a pipe 37 connected to the pipe 35, and the pipe 37 may extend to a manifold 39 with a valve 38 controlling the use or pressure of air. The manifold 39 is in a bracket 40 supporting one or more 50 rotary fans 42 and the fans have threaded stems 41 which may be mounted in the ends of gas supply pipes 44, after burners 43 are removed therefrom. Such a burner is shown in Fig. 9 and gas is ordinarily controlled to said burner by a valve 45. The 55 gas burner may form part of a conventional form of hot plate or cooking stove and the gas pipes may be used as convenient supports for the fans. Above the fan is a circular apertured air outlet pipe 46 communicating with the manifold 39 and air under pressure may drive the fan and cause a better circulation of air in a room.

Connected to the pistons 18 are piston 60 rods 20 extending through and guided by the partition 77, said rods being operatively connected by links 21 to the crank portions of a crank shaft 20 journaled in the partitions 7 and 8. On the ends of the crank 65 shaft within the end compartments 78, are

large gear wheels 63 meshing with small gear wheels 64 and 62, the former being loose on a spring motor shaft 48 and forming part of a sprocket wheel 65 loose on said shaft.

70 There are optional sources of power for driving the crank shaft 20 of the pump. One is an electric motor 69 under the stove shaft 70 at the end wall 5 of the casing. The other is one or two spring motors located in the top and bottom of the casing. The shaft 48 is part of the lower motor and another shaft 49 is part of the upper motor. The motors are somewhat identical, and about the shafts 48 and 49 are coiled springs 50, having end convolutions attached to the shafts, as at 51. Other end convolutions of the springs are attached to the hubs 52 of gear wheels 53 which are loose on the ends of the shafts 48 and 49. Meshing with the gear wheels 53 are gear wheels 54 slidably keyed on shafts 55, journaled in the end walls 5 and 6 and partitions 7 and 8 of the casing. The shafts 55 have shanks 60 on which may be mounted cranks or the like for rotating said shafts, and ratchet wheels 61 and pawls 61^a are adapted to prevent accidental rotation of said shafts.

80 The gear wheels 54 have hubs or sleeves 56 engaged by forks 57 carried by adjustable members 59 slidable in the walls 5 and 6 and on studs 58 carried by the partitions 7 and 8. With the gear wheels 54 and 53 in mesh the shafts 55 can be rotated to turn the shafts 48 and 49 and place the springs 50 under tension or wind said motor. With the gear wheels 54 shifted out of mesh with the gear wheels 53 the shafts 48 and 49 are free to be otherwise driven, for instance, by the electric motor 69 which is coupled direct 90 to said motor.

100 On the ends of the shaft 49, within the compartments 12, are sprocket wheels 66. On the ends of the shaft 48 are the sprocket wheels 65 and over the wheels 66 and 65 110 are trained sprocket chains 67 and 68, providing clearance for the crank shaft 20 and rod 82.

The spring motors may be inclosed by 115 tubular casing 47 connecting the partitions 7 and 8.

In operation and assuming the spring motors are to be used and have been wound or placed in an operative condition, the shaft 49 will drive the crank shaft 20 through the sprocket chain 68, sprocket wheel 65, shaft 48, and gear wheels 62 and 63. The shaft 48, actuated by the spring thereon will operate with the upper motor, and by this arrangement either spring motor can be 120 used.

125 Should either spring motor fail or it be desired to use the electric motor 69, then the gear wheels 54 are shifted out of mesh with the gear wheels 53, thus releasing the 130

shafts 48 and 49 from any spring actuation. When the motor is placed in operation it drives the shaft 49, sprocket chain 67, sprocket wheel 65 and gear wheels 64 and 63, the gear wheel 64 being part of said sprocket wheel. I prefer to depend on the electric motor 69 when electricity is available, otherwise the spring motors or the equivalent thereof may be used.

10 While in the drawings there is illustrated a preferred embodiment of my invention, it is to be understood that the structural elements are susceptible to such variations and modifications as fall within the scope of the 15 appended claims.

What I claim is:—

1. The combination with a range having a cooking top and an exhaust flue, of an attachment on the end of said range, said 20 attachment comprising a pump adapted to pump air into the flue of the range to produce a draft therein, a reservoir communicating with said pump, pipes communicating with said reservoir, means controlling the 25 communication between said pipes and said reservoir, means controlling the communication between said pump and the range flue, and means adapted to operate said pump,

said pump being of the multi-cylinder type with one of the cylinders exhausting fumes 30 from the cooking top of the range.

2. The combination with a range having a cooking top and an exhaust flue, of a pump at the end of the range, said pump having a cylinder adapted to exhaust fumes 35 from the cooking top of the range and another cylinder adapted to supply air to the exhaust flue of the range to produce a draft therein, and optional sources of power adapted to operate said pump.

3. The combination as in claim 2, wherein one of said sources of power is an electric motor.

4. The combination with a range having an exhaust flue, of a casing on the end of said range adapted to have air therein heated by the range, a pump in the casing adapted to pump heated air either into said range flue or to compartments adapted to be heated by air, and optional sources of power 50 adapted to operate said pump.

5. The combination set forth in claim 4, wherein one of said sources of power is an electric motor on the end of said casing.

In testimony whereof I affix my signature.
JOHN B. GAJ.
